INK MILL

Clarence R. Rechtin and Richard Jantsch, Cincinnati, Ohio, assignors to The J. H. Day Company, Cincinnati, Ohio, a corporation of Ohio

Application September 24, 1934, Serial No. 745,296
Renewed November 19, 1937

26 Claims. (Cl. 308—62)

This invention relates to a mill such as may be employed in the manufacture of inks, paints, and similar substances.

An object of the invention is to provide a mill 5 of the character stated, with means to facilitate cleaning the rolls thereof when necessary.

Another object of the invention is to provide such a mill embodying roll displacing means for the above purpose, which means, when actuated, 10 will not necessitate a subsequent micrometric re-setting of the mill rolls.

A further object of the invention is to provide a mill of the above stated character, with roll supporting and adjusting means so constructed 15 and arranged that an accurate setting of the rolls is secured and maintained even though the working parts of the mill become worn by reason of long or hard usage.

A further object of the invention is to provide 20 a mill of the character stated, which is simple, durable, and relatively inexpensive, and which may be operated easily and properly by operators not specially skilled in the art.

The foregoing and other objects are attained by 25 the means described herein and disclosed in the accompanying drawings, in which:

Fig. 1 is a side view of the machine of the invention, the side cover plates being omitted.

Fig. 2 is a fragmental cross-sectional view taken 30 on line 2—2 of Fig. 1.

Fig. 3 is a fragmental cross-sectional view taken on line 3—3 of Fig. 1.

Machines of the general character herein disclosed have been used for grinding pigment and 35 similar substances in the manufacture of inks and paints. The prior machines, however, were difficult to control, and whenever it became necessary to clean the rolls thereof or to separate the rolls for any reason, the micrometric setting of 40 the rolls was destroyed and had to be skillfully restored before the mill could be again placed in service. The present invention contemplates the use of novel means for preserving the micrometric setting of the rolls even though the rolls be shifted 45 relatively for cleaning or other purposes, said means being adapted also to facilitate the cleaning and re-setting operations. The means herein disclosed have the further advantage of automatically compensating for normal wear of the machine elements, so that accurate adjustments are 50 assured during the entire life of the machine.

The machine of the invention comprises a frame having spaced parallel uprights or standards 4 and 5 between which are disposed the 55 series of rolls 6, 7, 8, 9, and 10. In the operative

condition of the machine, the successive rolls are in line contacting relationship, adjusted so that adjacent rolls contact each other with a pressure that is uniform along the full length of the rolls. The adjustments between rolls are very 5 fine and accurate, so that a fine grinding action between successive rolls is attained. The adjustments may be progressively closer in the direction of the final or discharging roll 10, so that the product may be removed from the final roll 10 10 in any suitable manner, such as by means of a scraper 12, in a finished finely divided condition.

While the accompanying drawings show a machine having a group of five rolls, it is to be understood that the rolls may be increased or decreased in number, depending upon the nature of 15 the material to be treated and the characteristics to be imparted to the finished substance.

The pair of horizontal rolls 6 and 7, which are the feed rolls for material to be transferred to 20 the rolls 8, 9 and 10, may be more or less conventionally supported near the base of the machine. As disclosed, the rolls 6 and 7 have concentric axles 13 and 14, the opposite ends of which are supported in suitable bearing blocks 15 and 16. 25 The opposed bearing blocks 16 may be stationarily mounted in the frame whereas the pair of bearing blocks 15 may be slidably mounted in ways or guides 17. Two or more compression springs 18 may be provided for the purpose of normally urging the bearing blocks apart while a screw 19 provided with a hand wheel or other actuating means 20 serves as a means for moving roll 6 toward roll 7. The direction of rotation of rolls 6 and 7 is indicated by the arrows applied thereto.

The rolls 8, 9 and 10 may be referred to as transfer rolls, roll 8 being in substantial contact with feed roll 7 and with the cooperative transfer roll 9. The roll 9 is in turn disposed for normally 30 contacting the upper roll 10.

Each of the rolls 8, 9 and 10 is provided with a means for displacement thereof to an inoperative position for cleaning and other purposes and with a means for effecting accurate micrometric 40 setting relative to the next adjacent roll. Inasmuch as the displacing and adjusting means for each transfer roll operate upon the same principle, and comprise similar elements arranged merely in a reversed order, a detailed description thereof 45 relating to one transfer roll will suffice for the others also.

With reference to Figs. 1 and 2, the character 50 21 indicates an eccentric bearing box for the shaft end 22 of roll 10. Bearing box 21 may be 55

supported within a circular opening 23 provided in the vertical standard 4 of the machine frame, the opening and the circular bearing box being so related that the bearing box may freely be rotated within said opening. Fig. 1 shows the normal contacting position of roll 10 with roll 9, and in this position the axis 24 of shaft 22 is offset relative to the true center 25 of the bearing box. The centers 24 and 25 normally lie in a horizontal plane which includes that diameter of bearing box 21 which includes the axes 24 and 25. From the foregoing, it will be understood that a rotational movement of the eccentric bearing box 21 in a counter-clockwise direction about its true axis 25, will result in lifting the shaft 22 and its associated roll 10 from contacting relationship with the subjacent roll 9. In a like manner, roll 9 may subsequently be lifted from its position upon roll 8, and roll 8, in turn, may be lifted relative to the feed roll 7. The characters 26 indicate merely pairs of arcuate retaining means or end-thrust plates for maintaining the eccentric bearing boxes in their respective openings 21.

25 Each of the eccentric bearing boxes has operatively connected thereto a roll displacing means comprising a micrometric adjusting screw, which screws are designated by the characters 27, 28 and 29. The free or inner end 30 of each screw is threaded as indicated at 31, the threads being received by the cooperating threads of a nut 32 which is pivotally connected to the bearing box as indicated at 33. While any suitable means may be employed for pivotally mounting the nut relative to the bearing box, there is disclosed in Fig. 2 a crank member or eccentric mounting means 34 which is fixed relative to the eccentric bearing box. The member 34 may have a hub 35 which serves to maintain suitable anti-friction bearing means in position within the bearing box and about the shaft end 22. The member 34 may include also suitable packing rings 37 as shown, for precluding escape of lubricant from bearings. A sleeve 38 may be provided for clamping the race of the anti-friction bearing 36 and for spacing a driving gear such as 39 from the crank element 34. The gear may be keyed or otherwise fixed to the shaft end as indicated at 40. For a purpose to be hereafter explained, the threaded end of each micrometer screw has fixedly but adjustably mounted thereon, at opposite sides of the nut 32, the limit collars or stops 41 and 42, each of said collars or stops being spaced slightly from the opposite ends of the adjacent nut.

55 Each transfer roll is provided with a roll displacing means, to be actuated for quickly and completely spacing the rolls for cleaning and other purposes, as above mentioned. Said means comprises a pair of eccentrics or cams 43 and 44 each of which is fixedly mounted upon an end of a cam shaft 45 which extends transversely of the machine in substantial parallelism with the rolls, and has the bearing mountings 46 in the vertical standards of the frame. Each cam or eccentric has a bearing box 47 disposed about the periphery thereof, so that the cam may rotate therein without rotating the bearing box. Each bearing box is provided with a smooth bore 48 which rotatably receives the unthreaded shank of a micrometric adjusting screw 27, and the screw is precluded from longitudinal movement in said bore by means of collars or the like 49 and 50 which are secured to the screw shank. At accessible locations along the shaft 45 and

preferably near the vertical standards of the frame, the shaft has fixed thereto one or more hand levers 51 adapted to move in unison by reason of the connection with the cam shaft. Each hand lever is provided with an adjustable stop which may be in the form of a screw 52 movable with the hand lever and adapted to contact a stationary lug 53 carried by the frame of the machine. The adjustable stop means limits the downward movement of the hand lever, and determines the limit to which the cams or eccentrics 43 and 44 may be rotated in counter-clockwise direction. It is to be observed that in the normal or operative position of the hand levers as shown in Fig. 1 the axis of the cam shaft 45 and the true center of each of the cams secured thereto, lie in a plane which is parallel to the base of the machine, or perpendicular to the single vertical plane which includes the axes of all the transfer rolls 8, 9 and 10.

20 It is to be observed that the several pairs of roll-spacing cams 43 and 44, of the rolls 8, 9 and 10, may be made progressively larger or otherwise constructed to impart a greater movement to certain of the rolls in order to permit spacing 25 of the rolls from one another. For example, the throw of the uppermost pair of cams may approximate $\frac{3}{8}$ ", the one below, $\frac{1}{4}$ ", and of the third pair, $\frac{1}{8}$ ", thereby to allow substantially uniform spacings of approximately $\frac{1}{8}$ " between 30 all rolls when they are disposed in the inoperative or displaced positions. The distances or spacings above recited are by way of example only, to clarify the description, and it is by no means intended to limit the invention to the 35 specified distances of cam throw mentioned. The throw of the cams may be determined by their eccentricity rather than by their size, if desired. It is noteworthy that the cams or eccentrics 43 normally provide positive automatic 40 locks, for the rotatable roll bearings, due to their dead-center disposition as illustrated in Fig. 1.

Attention is now directed to the fact that the heel of the eccentric 21 which provides the bearing box for roll 10, faces the front of the machine, as does also the toe of the corresponding eccentric which provides the bearing box for roll 9. The corresponding eccentric for roll 8 is disposed similarly to that of roll 10. It is therefore evident that one pair of eccentrics is 45 reversed relative to the other two pairs, so that a lifting movement of roll 10 may be effected by rotating the eccentric bearing boxes thereof in counterclockwise direction (this being true also of the bearing boxes of roll 8), while a clockwise rotational movement is required of the bearing boxes of roll 9 in order to elevate roll 9 to the displaced or inoperative position. The reversed positions of the eccentric bearing boxes as just described precludes all possibility of any 50 back lash that would otherwise result from rotation of the rolls and their driving gears in opposite directions, as will be explained hereinafter. The construction provides also for maintaining the axes of all the transfer rolls in a common 55 plane.

Because of the peculiar disposition of the eccentric bearing boxes as above described, it is necessary to dispose the pairs of cams 43-44 of the quick-acting displacing means also in reversed and staggered relationship, as shown in Fig. 1. In order that all the hand wheels 56 may be rotated in the same direction to increase the pressure between rolls, left-hand threads are furnished on the micrometric adjustment screws 75

- 27 and 29, whereas right-hand threads are provided on the remaining screw 28. This construction eliminates any possible confusion in adjusting or resetting of rolls.
- 5 By means of the construction above described there is secured and maintained always an accurate setting of the rolls due to the fact that the rotational movement of each roll tends always to rotate its associated eccentric bearing box, with 0 the result that the threads of the micrometer screws and the threads of their cooperative nuts, can have no play or lost motion therebetween. The normally fixed stops or collars 41 and 42 which were referred to previously permit only 5 one or two turns of the micrometer adjustment screws within the nut or nuts 32, thereby precluding any exaggerated maladjustment of the rolls by means of the hand wheels. The characters 57 and 58 indicate respectively pointers and 10 graduated dials associated with the screws and the frame, whereby previous settings of the rolls may be repeated in the event changes are made by reason of the treatment of varying substances.
- 15 The driving means for the various rolls may comprise the main driving pinion 59 which is fixed to the main driving shaft 60, which shaft extends across the back of the machine and is adapted to receive rotational movement from 20 any suitable source of power, for example, a power driven pulley, sprocket or gear 61. If desired, a motor may be connected directly with the main drive shaft. The power-pinion 59 meshes with a gear 62 which is fixed on the 25 shaft of roll 9, and gear 62 in turn drives the gears 63 and 39 of rolls 8 and 10, respectively. Gear 63 meshes also with a gear 64 on the shaft of roll 7 and a second fixed gear 65 on said shaft drives a gear 66 which is fixed on the shaft of 30 roll 6. The gear train just described preferably is duplicated on the side of the machine opposite to that illustrated by Fig. 1. The quick-acting roll displacing means and the micrometric adjustment means also are duplicated on the 35 opposite side of the machine, as are also the bearing structures for all the rolls.
- The completed machine includes a lubricating system, gear covers or dust shields, cooling means for the rolls, etc., all of which is considered not 40 pertinent to the present invention and is therefore not illustrated or described.
- The operation of the machine is described as follows. With the gear train driven by means of a motor or other suitable power source, the substance to be treated is placed in the trough 45 formed between the two feed rolls 6 and 7. As these rolls rotate in the directions indicated by the small arrows, the substance (usually a liquid or semi-solid) is transferred by roll 7 onto roll 8, the transferring being continued by rolls 9 and 10 until finally the substance is removed from roll 10 by means of the scraper or remover 12. While the machine is thus operating, the 50 various hand wheels may be actuated to micrometrically adjust the force of the rolls upon one another so that the substance treated will be crushed and mixed uniformly along the full length of the rolls. The levers 51 will be in the positions shown, with their adjusting screws 52 in contact with their respective stops 53.
- Should it thereafter be necessary to clean the rolls, the operator grasps the levers 51, which move in pairs, and elevates them through an arc of about 90 degrees, beginning with the upper 55 pair, so that the top roll will first be lifted off
- of the next roll 9. Then the next pair of levers is elevated by the operator, to lift the roll 9 from contact with roll 8. As the throw of the cams associated with screw 28 is less than the throw of the corresponding cams 43 and 44 of the upper roll displacing unit, the roll 9 will not, when displaced, contact the upper roll 10. Similarly, actuation of the third or lowermost pair of levers 51 will cause the roll 8 to be lifted from the feed roll 7 without moving it into contact with 10 the previously displaced roll 9. If necessary, the handwheels 20 may be operated to separate the feed rolls 6 and 7. While all the rolls are thus separated or spaced apart, the driving gears remain in mesh sufficiently to rotate the rolls, and the rolls may then be wiped clean as they idle under the power of the driving means. After the rolls are cleaned, the feed rolls 6 and 7 may be returned to the feeding position, and all the transfer rolls moved quickly and accurately to 15 the original setting by means of the three pairs of levers 51, without disturbing the micrometric adjustment of the screws 27, 28 and 29. Thus the machine is replaced in service with a minimum loss of time and effort.
- 25 As stated before, the rolls are protected from injury and extreme mal-adjustment, by means of the stops or limiting collars 41 and 42 which are normally fixed upon the adjusting screw shafts in slightly spaced relationship at opposite 30 ends of the adjusting screw nuts, 32.
- It is to be understood that various modifications and changes in the structural details of the device may be made, within the scope of the appended claims, without departing from the 35 spirit of the invention.
- What is claimed is:
1. The combination of a frame, a plurality of superposed rolls having bearing ends, means supporting said bearing ends comprising pairs of circular bearing supports mounted for rotational movement relative to the frame, cooperative bearings associated with said supports and having their centers offset relative to the axes of rotation of the bearing supports, the bearing ends of the rolls being received in the said cooperative bearings, means for rotating certain of the bearing supports in unison, and associated means for rotating the bearing support, individually, the true centers of corresponding bearing supports being offset relatively, with the axes of the superposed rolls lying normally in a single upright plane.
- 40 2. In a device of the class described, the combination of a frame, a plurality of rolls having bearing ends, means supporting said bearing ends comprising bearing supports mounted for rotational movement relative to the frame, alternate ones of said bearing supports being reversed and having their centers offset relatively, cooperative 45 bearings for the roll bearing ends associated with said supports and having their axes offset relative to the centers of the bearing supports, the axes of said bearings for the roll bearing ends being disposed substantially in a single plane, means for rotating certain ones of the bearing supports in unison for displacing the rolls bodily, and relatively slow acting means operative for 50 rotating the bearing supports individually.
- 55 3. In a device of the class described, the combination of a frame, a plurality of rolls having bearing ends, means supporting said bearing ends comprising bearing supports mounted for rotational movement relative to the frame, alternate ones of said bearing supports being reversed and 55
- 60 4. In a device of the class described, the combination of a frame, a plurality of rolls having bearing ends, means supporting said bearing ends comprising bearing supports mounted for rotational movement relative to the frame, alternate ones of said bearing supports being reversed and 65
- 65 5. In a device of the class described, the combination of a frame, a plurality of rolls having bearing ends, means supporting said bearing ends comprising bearing supports mounted for rotational movement relative to the frame, alternate ones of said bearing supports being reversed and 70
- 70 6. In a device of the class described, the combination of a frame, a plurality of rolls having bearing ends, means supporting said bearing ends comprising bearing supports mounted for rotational movement relative to the frame, alternate ones of said bearing supports being reversed and 75

having their centers offset relatively, cooperative bearings for the roll-bearing ends associated with said supports and having their axes offset relative to the centers of the bearing supports, 5 the axes of said bearings for the roll bearing ends being disposed substantially in a single plane, means for rotating certain ones of the bearing supports in unison for displacing the rolls bodily, and relatively slow acting means operative for 10 rotating the bearing supports individually, and means associated with said individually operative means to impart opposite directions of rotation to adjacent bearing supports as said individually operative means are actuated in a common manner and direction.

4. In combination, a frame member, a roll having a bearing end, support means mounted rotatably relative to the frame member, for supporting said bearing end and comprising a perforation for reception of the bearing end of the roll, the perforation of said support being eccentric to the center of the support, a screw having a handle and threads, and means for mounting the screw upon the frame in substantial parallelism with a plane which passes through the center 25 of the support and the axis of the bearing perforation, a nut mounted for movement with the bearing support and disposed for engaging the threads of the screw whereby rotation of the 30 screw effects a rotation of the bearing support, and means for bodily shifting the screw mounting means substantially longitudinally, independently of actuation of the screw handle.

5. In combination, a frame member, a roll having a bearing end, support means mounted rotatably relative to the frame member for supporting said bearing end and comprising a perforation for reception of the bearing end of the roll, the perforation of said support being eccentric to the center of the support, a screw having a handle and threads, and means for mounting the screw upon the frame in substantial parallelism with a plane which passes through the center 45 of the support and the axis of the bearing perforation, a nut mounted for movement with the bearing support and disposed for engaging the threads of the screw whereby rotation of the screw effects a rotation of the bearing support, and means including a rotatable cam for bodily shifting the screw mounting means substantially longitudinally, independently of actuation of the screw handle.

6. In combination, a frame member, a roll having a bearing end, support means mounted 55 rotatably relative to the frame member for supporting said roll and comprising a perforation for reception of the bearing end of the roll, the perforation of said support being eccentric to the center of the support, a screw having a shank, a handle, and threads, a cam mounted for rotation relative to the frame and provided with means for rotating the cam, a bearing box associated with the cam and having a bore therein for reception of the screw shank, means precluding 60 longitudinal movement of the shank in the bearing box while permitting rotation of the shank therein, the support, the cam, and the bearing box being so related that the screw extends in substantial parallelism with a plane which passes 65 through the center of the support and the axis of the aforesaid perforation, a nut engaging the screw threads and means for mounting the nut upon the rotatable support.

7. In combination, a frame member, a roll 70 having a bearing end, support means mounted

rotatably relative to the frame member for supporting said roll and comprising a perforation for reception of the bearing end of the roll, the perforation of said support being eccentric to the center of the support, a screw having a shank, a handle, and threads, a cam mounted for rotation relative to the frame and provided with means for rotating the cam, a bearing box associated with the cam and having a bore therein for reception of the screw shank, means precluding 1 longitudinal movement of the shank in the bearing box while permitting rotation of the shank therein, the support, the cam, and the bearing box being so related that the screw extends in substantial parallelism with a plane which passes 1 through the center of the support and the axis of the aforesaid perforation, a nut engaging the screw threads and means for mounting the nut upon the rotatable support, and means for limiting the travel of the screw through the nut so as 2 to allow only a slight rotation of the rotatable support by reason of rotational movement of the screw.

8. A machine of the class described, comprising in combination, a frame member, a roll having a bearing end, support means for the roll mounted rotatably relative to the frame member, said support means having a perforation for rotatably receiving the bearing end of the roll, the perforation of said support means being eccentric to the true center of the support means, a screw having a shank, a handle, and threads, a nut carried by the support means and operatively engaging the threads of the screw, and means upon the frame including an eccentric mounting 3 for the screw shank in position to rotate the roll support means upon rotational movement of the screw, the eccentric mounting being adapted to advance and retract the screw longitudinally, and to assume a dead-center position locking the 4 screw at one limit of its longitudinal travel.

9. A machine comprising in combination, a frame member, a roll having a bearing end, support means for the roll mounted rotatably relative to the frame member, said support means having a perforation for rotatably receiving the bearing end of the roll, the perforation of said support means being eccentric to the true center of the support means, a screw having a shank, a handle, and threads, a nut carried by the support means and operatively engaging the threads of the screw, and means supported upon the frame member in position to rotate the roll support means upon both rotational and longitudinal movement of the screw, said last mentioned means including an eccentric having a quicker throw movement than the screw threads.

10. In a machine of the class described, the combination of a frame, a roll bearing means mounted upon the frame for shifting movement, a rotatable adjusting member for the bearing means, cooperative engaging screw threaded means on the adjusting member and the bearing means for adjusting the position of the bearing means by rotation of the adjusting member, a rotatable cam shaft supported upon the frame substantially perpendicularly to the axis of rotation of the rotatable adjusting member, a cam on said shaft, a box having a circular bore rotatably housing said cam, a bearing carried by said box and receiving the rotatable adjusting member, and means for normally precluding longitudinal movement of the adjusting member in the last mentioned bearing.

11. In a machine of the class described, the

combination of a frame, a roll bearing means mounted upon the frame for shifting movement, a screw threaded nut carried by and movable with the roll bearing means, a screw comprising a threaded end engaging the threads of the nut, a shank portion, and a manipulating means on the screw, a rotatable shaft supported upon the frame substantially perpendicularly to the screw, a circular disc eccentrically mounted upon said shaft, a bearing box having a circular bore rotatably supporting said disc and a second bore rotatably supporting the screw shank, means for rotating the eccentrically mounted disc within the first mentioned bore of the bearing box, and means for normally precluding longitudinal movement of the screw shank through the second mentioned bore of the bearing box.

12. In a machine of the class described, the combination of a frame, a transfer roll rotatably mounted upon the frame, a second roll and shiftable bearing means therefor whereby said second roll may be moved to and from a working position with respect to the first roll, a rotatable adjusting member for said shiftable bearing means, cooperative engaging screw threaded means on the adjusting member and the bearing means for varying the position of the bearing means by rotation of the adjusting member, a rotatable cam shaft supported upon the frame substantially perpendicularly to the axis of rotation of the adjusting member, a cam on said shaft having a toe and a heel, a box having a circular bore rotatably housing said cam, a bearing carried by said box and receiving the rotatable adjusting member, means for normally precluding longitudinal movement of the adjusting member in the bearing of the box, the heel and toe of the cam being so related to the box bearing as to assume a dead center relationship with the axis of the adjusting member when the rolls are disposed in working position.

13. In a roller mill having a frame and a series of superposed rolls supported thereon with their axes in a single upright plane, the combination of pairs of supports for the opposite ends of the rolls, said supports being circular and rotatable relative to the frame, with the centers of the roll supports staggered and lying at opposite sides of the plane of the roll axes, and means for rotating adjacent roll supports in opposite directions of rotation for spacing the rolls apart.

14. In a roller mill having a frame and a series of superposed rolls supported thereon with their axes in a single upright plane, the combination of pairs of supports for the opposite ends of the rolls, said supports being circular and rotatable relative to the frame, with the centers of the roll supports staggered and lying at opposite sides of the plane of the roll axes, and means for rotating adjacent roll supports in opposite directions of rotation for spacing the rolls apart, said means including a series of quick-acting eccentric devices each connected to a roll support and movable to a dead-center position at which the roll support is locked against accidental rotation.

15. In a roller mill having a frame and a series of superposed rolls supported thereon with their axes in a single upright plane, the combination of pairs of supports for the opposite ends of the rolls, said supports being circular and rotatable relative to the frame, with the centers of the roll supports staggered and lying at opposite sides of the plane of the roll axes, and means for rotating adjacent roll supports in opposite directions of rotation for spacing the rolls apart, said

means including a series of quick-acting eccentric devices each connected to a roll support and movable to a dead-center position at which the roll support is locked against accidental rotation, and a second means for rotating the roll supports while the other roll support rotating means is in the dead-center position.

16. A machine of the character described comprising in combination: a frame member, a roll having a bearing end, support means for the roll mounted rotatably relative to the frame member, the axis of rotation of the bearing end of the roll being eccentric to the center of the rotatable support means, an adjustment shaft having opposite ends, one of which ends is adapted for manipulation by hand, and the other of which adjustably connects with the roll support means, for advancement and retraction of the support means along an arc upon rotation of said shaft in opposite directions, and a cam device movable to a dead-center position and operatively connected with the adjustment shaft to shift it longitudinally independently of its rotational movement, the dead-center position of the cam device serving to lock the shaft against longitudinal shifting in one direction.

17. A machine of the character described comprising in combination, a frame member, a roll having a bearing end, support means for the roll mounted rotatably relative to the frame member, said support means having a bore for rotatably receiving the bearing end of the roll, the bore of said support means being eccentric to the true center of the support means, a screw having a shank, a handle, and threads, a nut carried by the support means and operatively engaging the threads of the screw, the nut being rockably mounted at one side of the axis of rotation of the support means, a selectively shiftable bearing means on the frame member snugly embracing the screw shank for rotational movement of said shank with a close bearing fit, and means precluding lengthwise movement of the screw in said bearing means.

18. In a device of the class described, the combination of a frame, a plurality of rolls having bearing ends, means supporting said bearing ends comprising bearing supports mounted for rotational movement relative to the frame, alternate ones of said bearing supports being reversed and having their centers offset relatively, cooperative bearings for the roll-bearing ends associated with said supports and having their axes offset relative to the centers of the bearing supports, the axes of said bearings for the roll bearing ends being disposed substantially in a single plane, means for rotating certain ones of the bearing supports in unison for displacing the rolls bodily, and relatively slow acting means operative for rotating the bearing supports individually, each including a screw shaft and a nut, to impart opposite directions of rotation to adjacent bearing supports upon actuation of said slow acting means in a common manner and direction to effect roll contact adjustments, and gearing for driving the rolls and tending to rotate each roll support in a direction opposing roll advancing movement of said slow acting means.

19. In a roller mill having a frame and a series of superposed rolls supported thereon with their axes in a single upright plane, the combination of pairs of supports for the opposite ends of the rolls, said supports being circular and rotatable relative to the frame, with the centers of the roll supports staggered and lying at opposite sides of the plane of the roll axes, and means for rotating adjacent roll supports in opposite directions of rotation for spacing the rolls apart, 70

supports staggered and lying at opposite sides of the plane of the roll axes, and means for rotating adjacent roll supports in opposite directions of rotation for spacing the rolls apart, said means including a series of quick-acting eccentric devices each connected to a roll support and movable to a dead-center position at which the roll support is locked against accidental rotation, and relatively slow acting means manipulatable to impart opposite directions of rotation to adjacent bearing supports upon actuation of said slow acting means in a common manner and direction to effect roll contact adjustments, and gearing for driving the rolls and tending to rotate each roll support in a direction opposing roll advancing movement of said slow acting means.

20. In a roller mill having a frame and a series of superposed rolls supported thereon with their axes in a single upright plane, the combination of pairs of supports for the opposite ends of the rolls, said supports being circular and rotatable relative to the frame, with the centers of the roll supports staggered and lying at opposite sides of the plane of the roll axes, and means including a series of eccentrics each having a different throw value, for rotating adjacent roll supports various distances in opposite directions of rotation for spacing the rolls apart.

21. In a roller mill having a frame and a series of superposed rolls supported thereon with their axes in a single upright plane, the combination of pairs of supports for the opposite ends of the rolls, said supports being circular and rotatable relative to the frame, with the centers of the roll supports staggered and lying at opposite sides of the plane of the roll axes, and means for rotating adjacent roll supports in opposite directions of rotation for spacing the rolls apart, said means including a series of quick-acting eccentric devices each having a different throw value, and connected to a roll support and movable to a dead-center position at which the roll support is locked against accidental rotation.

22. In a machine of the class described, the combination of a frame, a series of roll bearing means mounted upon the frame for shifting movement, a rotatable adjusting member for each of the bearing means, cooperative engaging screw threaded means on each adjusting member and its associated bearing means for adjusting the position of the bearing means by rotation of the adjusting members, a series of rotatable cam shafts each supported by the frame substantially perpendicularly to the axis of rotation of a rotatable adjusting member, a cam on each shaft, each of said cams having a different throw value, a box having a circular bore rotatably housing each cam, a bearing carried by each box and receiving one of the rotatable adjusting members, and means for normally precluding longitudinal movement of the adjusting member in the last mentioned bearing.

23. A roller mill comprising a frame and a plurality of rotatable rolls, roll supporting bearings shiftably mounted upon the frame for supporting the rolls in substantial parallelism, and means for shifting said roll supporting bearings and the rolls supported thereby, to alter the spacing between the rolls, said means comprising a rotatable eccentric for each roll and connecting

means between the eccentrics and the roll supporting bearings for translating rotational movement of the eccentrics into shifting movement of the roll supporting bearings, the eccentrics for the different rolls having different throw values, assuring differing extents of roll supporting bearing shiftability upon rotation of the eccentrics through substantially equal arcs of rotation.

24. A roller mill comprising a frame and a plurality of rotatable rolls, roll supporting bearings shiftably mounted upon the frame for supporting the rolls in substantial parallelism, and means for shifting said roll supporting bearings and the rolls supported thereby, to alter the spacing between the rolls, said means comprising a rotatable eccentric for each roll and connecting means between the eccentrics and the roll supporting bearings for translating rotational movement of the eccentrics into shifting movement of the roll supporting bearings, the eccentrics for the different rolls having different throw values, assuring differing extents of roll supporting bearing shiftability upon rotation of the eccentrics through substantially equal arcs of rotation, and means for rotating the eccentrics toward and from dead-center holding relationship to the roll supporting bearings.

25. A roller mill comprising a frame and a plurality of rotatable rolls, roll supporting bearings shiftably mounted upon the frame for supporting the rolls in substantial parallelism, and means for shifting said roll supporting bearings and the rolls supported thereby, to alter the spacing between the rolls, said means comprising a rotatable eccentric for each roll and connecting means between the eccentrics and the roll supporting bearings for translating rotational movement of the eccentrics into shifting movement of the roll supporting bearings, the eccentrics for the different rolls having different throw values, assuring differing extents of roll supporting bearing shiftability upon rotation of the eccentrics through substantially equal arcs of rotation, and comparatively slow acting means for shifting said roll supporting bearings while the eccentrics remain in a state of rest.

26. A roller mill comprising a frame and a plurality of rotatable rolls, roll supporting bearings shiftably mounted upon the frame for supporting the rolls in substantial parallelism, and means for shifting said roll supporting bearings and the rolls supported thereby, to alter the spacing between the rolls, said means comprising a rotatable eccentric for each roll and connecting means between the eccentrics and the roll supporting bearings for translating rotational movement of the eccentrics into shifting movement of the roll supporting bearings, the eccentrics for the different rolls having different throw values, assuring differing extents of roll supporting bearing shiftability upon rotation of the eccentrics through substantially equal arcs of rotation, and additional roll supporting bearing shifting means operative individually upon the bearings at opposite ends of the rolls for equalizing the force of roll contact at opposite ends of the contacting rolls.
